ROSS M. G. PHILLIPS, OF WEST HAVEN, CONNECTICUT, ASSIGNOR TO THE AUTOMATIC STOVE CO., OF MINNEAPOLIS, MINNESOTA, A CORPORATION.

COOKING APPARATUS.

14,161.

Specification of Reissued Letters Patent. Reissued July 4, 1916.

Original No. 1,102,796, dated July 7, 1914, Serial No. 710,630. Application for reissue filed March 6, 1916. Serial No. 82,488.

To all whom it may concern:

Be it known that I, Ross M. G. PHILLIPS, a citizen of the United States, residing at West Haven, Connecticut, formerly residing 5 at Minneapolis, in the county of Hennepin and State of Minnesota, have invented a new and useful Improvement in Cooking Apparatus, of which the following is a specification.

10 The object of this invention is the production of a portable cooker having means whereby it can be used with or without a fire.

Further objects are, automatic control of 15 the fire which is used and of the draft passage therefor, simplicity of construction and effectiveness and convenience in use.

Heretofore it has been usual to place a 20 preheated stone in portable stoves for cooking purposes or to use a fire in a stove without the stone. With my invention the fire is used for heating the stove and stone together thus producing greater efficiency and economy and avoiding all handling of the 25 stone. After the stone has been heated the device is adapted to be used effectively as a fireless cooker.

In the accompanying drawings forming 30 part of this specification, Figure 1 is a plan view of my invention, Fig. 2 is a front elevation, Fig. 3 is a section on the line X—X, Fig. 1, the parts being shown when in open position, Fig. 4 is a similar section when the 35 parts are in closed position, Fig. 5 is a plan of the supporting sleeve and lever for the insulated receptacle, Fig. 6 is a detail in section showing a portion of the insulated receptacle, Fig. 7 is another detail in section showing the tray as withdrawn to expose the pre-heater for lighting, Fig. 8 is a detail showing part of the timer mechanism for closing the receptacle automatically, Fig. 40 9 is a plan of the construction illustrated in Fig. 8, Fig. 10 is a section of a detail showing 45 the construction of guides employed for part of the operating arms illustrated in Fig. 8, Fig. 11 is a side view in section of the fuel measuring cup, Fig. 12 is a section upon the line Y—Y, Fig. 11, Fig. 13 is a 50 section of a detail showing the construction of the stopper valve employed in the cover of the receptacle, and Fig. 14 is a front elevation of an alternative construction of my invention.

In the drawings A indicates a suitable 55 outer casing having an open top and formed with a door way 2 near the lower portion of one of its sides. A tray 3 is adapted to slide on the bottom 4 of the casing through the door way, its end 5 projecting below the 60 door 6 in the door way so that it can be used as a handle to draw the tray out or push it into the casing. This tray is adapted to carry a pre-heater B of suitable construction such as an alcohol stove. The rim 65 of the casing extends inwardly and is turned down to form a centrally disposed depending cylindrical wall 7 in which an insulated food-container or receptacle C is adapted to move freely. This receptacle has a double 70 side and bottom wall, the space between the adjacent inner faces of said walls being filled with a suitable poor heat conducting material 8 such as ground cork. The bottom of the receptacle is formed with a centrally disposed opening or ingress draft- 75 passage 9 fitting over the pre-heater B and its top is closed by a removable cover 10 having double walls spaced apart for insulating purposes. The burner B is provided with a circular sealing and insulating pad F made of asbestos or equivalent material and considerably larger in diameter than the ingress draft-passage 9 in the food-container, so that when the same is brought 80 in its descent to a bearing upon the said pad, the said pad not only closes and seals the ingress draft-passage 9, but also insulates the food-container and thus retards the 85 radiation of heat therefrom.

The cover is provided with an egress draft passage 11 which is adapted to be closed by an automatically operated valve 12 said valve being formed with a stem 13 sliding freely through the handle 14. An expansion 95 spring 15 compressed between the handle and valve proper tends to keep the valve in closed position. The valve stem and valve proper are formed with a vent opening 16 for steam from within the receptacle which 100 can be closed by a thumb screw 17 (see Fig. 6). The valve is held in open position by a hook 18 having a shaft 19 journaled in supports on the top of the cover, said hook being adapted to engage in an eye 20 carried by the valve. The outer end of the shaft is formed with a depending arm 21 hanging from the edge of the cover and

adapted to impinge against the bracket 22 fixed on the top of the casing to disengage the catch from the valve when the receptacle C lowers from superior position as shown in Fig. 3, to closed position as shown in Fig. 4. The said valve 12 must be manually set after the cover 10 has been placed upon the food-container C and the same has been suspended in spaced relation to the pre-heater B by means of the spacing-mechanism to be described later on. But the action of the said valve in closing is automatic.

The receptacle or food-container C is adapted to be seated in a sleeve D which in turn is supported freely within the wall 7 by a yoke or forked lever 23 fulcrumed by links 24 which are pivoted to the ends of the fork and to brackets 25 secured to the top of the casing. The lever is pivoted adjacent its ends at diametrically opposite points 26 to the side of the sleeve D. The body portion of the lever is secured freely by an angle 27 to the vertically movable supporting or lifting rod 28. This rod depends freely through an opening 29 (see Fig. 8) in the top wall of the casing and is formed with a catch shoulder 30 adapted to engage over the edge 31 of said opening to hold the body of the lever up and the receptacle in superior or spaced position so that a draft opening is formed between the pre-heater and receptacle. The upper end of the rod 28 is provided with a lifting handle 32 by which the rod can be raised. Guides in the form of flanges 33 (see Fig. 10) on the side edges of the opening 29 limit side movement of the rod 28 and prevent the shoulder 30 from engaging over the edge of said opening except on one side. A portion 34 of the shoulder 30 also serves for the same purpose. The mechanism just above described for the suspension of the food-container, constitutes a spacing mechanism since its function is to maintain the food-container in spaced relation to the preheater during the heat-charging period.

A fuel tank 35 is supported in the space between the outer wall of the casing and the inner wall 7 and has a plugged filling opening 36 for alcohol and a supply pipe 37 leading to a measuring cup 38 by which the desired amount of alcohol may be gaged for use in the heater. A valve 39 (see Figs. 2, 3, 4 and 11) controlled by handle 40 is adapted to open the cup through the nozzle 41 and discharge a supply of fuel to the preheater when the latter has been drawn out by the tray 3 through opening 2 into the position shown in Fig. 7. The valve 39 is adapted when in normal position of the handle to open the supply pipe 37 and close the nozzle and vice versa when turned to close the supply pipe to open the nozzle.

The timing mechanism E is adapted to release the lever 23 and drop the receptacle

and employs a clock work mechanism 42 of ordinary construction. This mechanism pushes the rod 28 out of engagement with edge 31 at a predetermined time by push rod or latch 43 which is slidably and pivotally mounted on the pin 44 on the wall of the casing A. The push rod 43 co-operates with a link 45 to form a pair of toggle levers the connected ends of which being pivoted at 46 to an actuating link 47. This link is pivotally mounted on an arm or tripping-lever 48 one end of which is fulcrumed at 49 on casing A and its free end provided with a handle 50 projecting through and movable in a slot 51 in the casing. Near the free end of the arm 48 is a stop or timing-pin 52 adapted to drop into the notch 53 in the periphery of the stop or timing-disk or wheel 54 carried by the main drive shaft 55 of the clock work mechanism.

The winding crank handle or setting-lever 56 on shaft 55 is adapted to be moved in the direction indicated by arrows in Figs. 2 and 8 a portion of a turn according to the length of time the preheater is to be operated, the degree of turn as illustrated being marked "15" and "30" (indicating minutes) upon the casing A. The rod 28 after this operation is then raised into the position indicated in Fig. 8, the valve 12 is opened and the preheater ignited. The clock work mechanism turns the shaft 55 until the stop 52 engages notch 53 and stops the clock work mechanism. As stop 52 engages notch 53 the rod 28 is disengaged from edge 31 allowing the receptacle to drop by gravity and close the opening 9. The closing movement of the receptacle releases the hook 18 from engagement with eye 20 thus permitting valve 12 to close automatically.

The arm 48 is drawn upwardly by a spring 57 and before setting the timer E the handle 50 is pressed down to disengage the stop 52 from notch 53 in disk 54. A stand 58 of skeleton form is placed in the bottom of the receptacle upon which a heat conserver 59 is placed and held in central position, said conserver consisting of soap stone or metal as desired and being spaced from the opening 9 to admit of a draft passage from the preheater into the receptacle. A cooking utensil 60 of any desired form may be employed in the receptacle. To open the device the cover is removed and the receptacle can be lifted out of the sleeve. To forestall, as it were, or anticipate the action of the automatic controlling mechanism as may be for one reason or another sometimes desired, it is only necessary to move the handle 32 laterally from left to right so as to move the lifting rod 28 and disengage the spacing-shoulder 30 from the edge 31 of the opening 29. The weight of the food-container now will cause it to descend into its heat-conserving position in which its draft passages 130

will be closed and the preheater extinguished in advance, as it were, of the tripping-action of the automatic controlling mechanism. In this way the spacing-mechanism fulfils the 5 secondary function of forestalling means to anticipate the releasing action of the automatic time-limiting mechanism.

In the alternative construction shown in Fig. 14, the casing 61 is made to accommodate 10 two receptacles and a single clock work mechanism E is employed to operate both receptacles. A pair of long toggle levers F is connected to the arm 48. This set of levers consists of a push bar 62 which is 15 slidingly mounted on the casing and adapted to disengage the rods 28 simultaneously and is actuated by a link 63 connected pivotally to arm 48 and link 64. This actuating means operates in every way similar to 20 the mechanism described in the preferred form.

In my improved cooker as shown herein, I employ a vertically movable cooking receptacle having an ingress opening at its 25 lower end and an egress opening at its upper end, in combination with means for suspending the said receptacle in an elevated position over a preheater from which it is thus sufficiently separated to form a draft 30 passage between the preheater and the ingress opening in the bottom of the receptacle. This draft passage is eliminated and the ingress passage in the receptacle closed by the descent of the receptacle at a predetermined time following the tripping, so to speak, of the mechanism employed to suspend it in its elevated or heat-charging position. As herein shown, also, I utilize the descent of the receptacle for the actuation 40 of means for closing and sealing the egress opening at its upper end at the time it descends into its heat-conserving position. The preheater or burner, whatever its character may be, is carried, as shown, by a 45 horizontally movable tray or slide mounted in the casing of the cooker and located below the plane of the bottom of the receptacle. When the cooker is in its suspended or heat-charging position and the tray is 50 in its closed position, a draft-passage is formed between the preheater and the ingress opening in the bottom of the said receptacle the descent of which eliminates the said draft-passage and closes the said ingress-opening. When the said receptacle 55 is in its said suspended position the tray may be drawn outward from under the receptacle or retracted to expose the preheater for lighting the same, after which it is 60 pushed back into place under the receptacle. This lateral movement of the tray and preheater can take place only when the receptacle is in its elevated or heat-charging position. When the receptacle is in its lowered 65 or heat-conserving position it rests upon

and is supported by the preheater which then closes its ingress opening and so conserves its heat.

In accordance with the patent statutes I have described the principles of operation 70 of my invention together with the apparatus which I now consider to represent the best embodiment thereof but I desire to have it understood that the construction shown is only illustrative and that the invention 75 can be carried out by other means and applied to uses other than those above set forth within the scope of the following claims.

I do not in this case claim in a cooking 80 apparatus of the character shown and described, means for automatically supplying fuel to the preheater and automatically cutting off such supply, those features being claimed in my copending application filed 85 December 21, 1912, Serial No. 737,993, which shows but does not broadly claim, the typical apparatus shown and described herein. On the lapsing of the co-pending application above referred to, it was renewed and 90 given the filing date of August 14, 1915, Serial No. 45,572.

My improved conjoint fire- and fireless-cooking apparatus, when broadly viewed, is characterized by its adaptability to be manually set in accordance with the varying demands of ordinary cooking, and by its provision with means whereby the transition from fire-cooking to fireless-cooking is automatically effected in consonance with the 100 specific manner in which it was set by the user of it.

My improved apparatus is further characterized by its provision for the draft required for the combustion of the fuel during the period of fire-cooking and by its provision for being sealed or virtually sealed for the conservation of its retained heat during the period of fireless-cooking. 105

My apparatus is further characterized by the control of the fuel which cannot be brought into use for cooking until after the apparatus has been set for a cooking operation. 110

The "spacing apparatus" referred to in 115 the foregoing text, was so named because it provided for the creation, in the specific apparatus described, of the space required for the ingress of the air required for combustion. That, however, is but one minor 120 function of the so called spacing-apparatus which has a superior function in storing the energy (here represented by gravity) required for converting the apparatus from an apparatus for fire-cooking into an apparatus 125 for fireless-cooking, the energy so stored being restrained by cocking means (here represented by the rod 28 and the shoulder 30) which are also relied upon to maintain the draft conditions required for fire-cooking. 130

My invention is further characterized by the employment of cocking, energy storing, and automatic releasing means, the latter being adapted to be manually set according 5 to the demands of ordinary cooking, and to effect the automatic release of the cocking means so as to liberate the energy required for the described conversion of the apparatus.

10 In other words, my invention broadly comprehends an apparatus for conjoint fire- and fireless-cooking in which the apparatus is adapted to be manually set as required by the demands of ordinary cooking and 15 automatically converted from an apparatus for fire-cooking to an apparatus for fireless-cooking at the end of the prearranged period of fire-cooking.

Having described my invention, what I 20 claim as new and desire to protect by Letters Patent is:

1. In a cooking apparatus, the combination with a food-container having ingress and egress draft-passages, of a preheater, 25 one of the said parts being movable with respect to the other for the creation and closure of a draft-space between them, a spacing mechanism for holding the said movable part in spaced relation to the other 30 part, and means for automatically controlling the releasing function of the said spacing mechanism.

2. In a cooking apparatus, the combination with a food-container having ingress 35 and egress draft-passages and adapted to receive a radiator, of a preheater, one of the said parts being movable with respect to the other for the creation and closure of a draft-space between them, spacing-mechanism for 40 holding the said movable part in spaced relation to the other part, and means for automatically controlling the releasing function of the spacing-mechanism.

3. In a cooking apparatus, the combination with a food-container having ingress and egress draft-passages, of a preheater adapted to act as a closure for the said ingress passage, the said parts being movable with respect to each other for the creation 50 and closure of a draft-space between them, spacing mechanism for holding the said movable part in spaced relation to the other part, and means for automatically controlling the releasing function of the said spacing-mechanism.

4. In a cooking apparatus, the combination with a vertically movable food-container formed at its lower end with an ingress draft-passage, of a preheater adapted 60 to act as a closure for the said ingress draft-passage, spacing-mechanism for holding the food-container above the preheater in spaced relation thereto, and means for automatically controlling the function of the spacing-mechanism in releasing the container which

descends upon the preheater for the closing of its said draft ingress passage.

5. In a cooking apparatus, the combination with a food-container having ingress and egress draft-passages, of a preheater 70 adapted to act as a closure for the said ingress draft-passage, one of the said parts being movable with respect to the other, spacing-mechanism for holding the said movable part in spaced relation to the other part, means for automatically controlling the releasing function of the spacing mechanism, and means for automatically closing the said egress draft-passage when the container and preheater are moved together. 80

6. In a cooking apparatus, the combination with a food container having an ingress draft-passage, of a preheater adapted to act as a closure for the said ingress draft-passage, one of the said parts being movable 85 with respect to the other, spacing-mechanism for holding the container and preheater in spaced relation, means for automatically controlling the releasing function of the spacing-mechanism, and means for insulating the container and preheater when moved together for the closure of the said ingress draft-passage.

7. In a cooking apparatus, the combination with a food-container having an ingress draft-passage and a preheater adapted to constitute a closure for the said passage, one of said parts being movable with respect to the other for the creation and closure of a draft-space between them, and the preheater being also movable into a lighting position; of a spacing-mechanism for holding the said movable part in spaced relation to the other part, and means for automatically controlling the releasing function of the spacing-mechanism. 100

8. In a cooking apparatus, the combination with a food-container having an ingress draft-passage, of a laterally movable preheater adapted to act as a closure for the said passage one of the said parts being movable with respect to the other for the creation and closure of a draft-space between them, spacing-mechanism for holding the said container and preheater in spaced relation, means for automatically controlling the releasing function of the spacing-mechanism, and means for moving the preheater laterally with respect to the container into its lighting position. 110

9. In a cooking apparatus, the combination with a food-container having ingress and egress draft-passages, of a preheater adapted to close the said ingress draft-passage one of the said parts being movable with respect to the other, spacing-mechanism for holding the said container and preheater in spaced relation, means for automatically controlling the releasing function of the said spacing-mechanism, and an in- 115 120 125 130

5 insulating member carried by the said pre-heater and insulating the same from the container when the two parts are closed together for the closure of the said ingress draft-passage.

10 10. In a cooking apparatus, the combination with a vertically movable food-container having an ingress and an egress draft-passage, of a preheater adapted to close the said ingress draft-passage, spacing-mechanism for holding the container in spaced relation above the preheater, means for automatically controlling the releasing function of the spacing-mechanism, and means controlled by the descent of the container for automatically closing the egress draft passage thereof concurrently with the closing of the ingress passage thereof by the preheater.

15 11. In a cooking apparatus, the combination with a casing, of a vertically movable food-container having ingress and egress draft-passages, a laterally movable tray, a preheater thereupon adapted to close the ingress draft-passage of the container and moved into its lighting position outside of the said casing when the tray is retracted therefrom, spacing-mechanism for holding the container in spaced relation above the preheater, and means for automatically controlling the releasing function of the spacing-mechanism for the descent of the container upon the preheater.

20 12. In a cooking apparatus, the combination with a vertically movable food-container having ingress and egress draft-passages, of a preheater adapted to act as a closure for the said ingress passage, spacing-mechanism for holding the said container in spaced relation above the preheater, the said mechanism including a vertically movable handle, and automatic means co-operating with the said handle for releasing the container to permit its descent for the closure of its draft-passage by the preheater.

25 13. In a cooking apparatus, the combination with a vertically movable food-container having an ingress draft-passage in its lower end, of a preheater adapted to act as a closure for the said draft-passage, spacing-mechanism for holding the container in spaced relation above the preheater, the said spacing-mechanism including a lever and a vertically movable handle, and automatic means co-acting with the said handle for releasing the container to permit its descent for the closure of its ingress draft-passage by the preheater.

30 14. In a cooking apparatus, the combination with a casing, of a vertically movable food-container having an ingress draft-passage in its lower end, a tray laterally movable in the said casing and provided at its outer end with a door, a preheater carried

35 by the said tray and adapted to act as a closure for the said ingress draft-passage of the container, spacing-mechanism for holding the container in spaced relation above the preheater, and means for automatically 70 controlling the releasing function of the spacing-mechanism.

40 15. In a cooking apparatus, the combination with a vertically movable food-container having an ingress draft-passage at its lower end and an egress draft-passage in the cover provided for its upper end, of a preheater adapted to act as a closure for the said ingress draft-passage, spacing-mechanism for holding the container in spaced relation above the preheater, means for automatically controlling the releasing function of the spacing-mechanism, a valve for closing the said egress draft-passage, and means for automatically closing the said valve upon 80 the descent of the food-container.

45 16. In a cooking apparatus, the combination with a casing, of a vertically movable food-container having an ingress draft-passage in its lower end and provided with a removable cover having an egress draft-passage, of a preheater adapted to act as a closure for the said ingress draft-passage, spacing-mechanism for holding the container in spaced relation above the preheater, means for automatically controlling the releasing function of the said spacing-mechanism, a valve for the said egress draft-passage, means mounted upon the cover of the container for carrying the said valve, 100 and means for automatically closing the said valve concurrently with the descent of the container for the closure of its ingress draft-passage by the said preheater.

50 17. In a cooking apparatus, the combination with a food-container having ingress and egress draft-passages, of a sleeve in which the said container is suspended, a preheater adapted to act as a closure for the said ingress draft-passage, spacing-mechanism for lifting the said sleeve and container and holding the same in spaced relation above the preheater, means for automatically controlling the releasing function of the spacing-mechanism, and means for 110 closing the egress openings of the container when the same is released for the closure of its ingress draft-passage.

55 18. In a cooking apparatus, the combination with a casing, of a vertically movable food-container having an ingress draft-passage in its lower end and provided with a removable cover having an egress draft-passage, a preheater adapted to act as a closure for the said ingress draft-passage, 120 spacing-mechanism for holding the container in spaced relation above the preheater, means for automatically controlling the releasing function of the said spacing-mechanism, a vented valve for the said 125

60 190

egress draft-passage, and a lever mounted upon the said cover, carrying the said vented valve and engaged by a part of the casing for automatically closing the said valve upon the descent of the container for the closure of its ingress draft-passage by the preheater.

19. In a cooking apparatus, the combination with a casing, of a vertically movable food-container having an ingress draft-passage in its lower end and provided with a removable cover having an egress draft-passage, a preheater acting as a closure for the said ingress draft-passage and laterally movable into a lighting position outside of the casing, spacing-mechanism for holding the container in spaced relation above the preheater, means for automatically controlling the releasing function of the spacing-mechanism, and means for automatically closing the egress passage in the cover of the container when the same descends for the closure of its ingress draft-passage by the preheater.

20. In a cooking apparatus, the combination with a casing, of a food-container and a preheater one of which parts is movable with respect to the other for the creation and closure of a draft space between them, spacing-mechanism for holding the said movable part in spaced relation to the other part, means for automatically controlling the releasing function of the spacing-mechanism, and means for manually forestalling the action of the said automatic means in releasing the said spacing-mechanism.

21. In a cooking apparatus, the combination with a casing, of a vertically movable food-container, a preheater, spacing-mechanism for holding the said container in spaced relation above the said preheater for the creation and closure of a draft-space between them, means for automatically controlling the releasing function of the said spacing-mechanism, and means for manually forestalling the action of the said automatic mechanism in releasing the container.

22. In a cooking apparatus, the combination with a casing, of a vertically movable food-container having ingress and egress draft-passages, a laterally movable preheater adapted to act as a closure for the said ingress draft-passage, spacing-mechanism for holding the said container in spaced relation above the preheater, means for automatically controlling the releasing function of the spacing-mechanism, a fuel reservoir located within the casing, and means for supplying fuel to the preheater from the said reservoir when the preheater is moved laterally with respect to the container.

23. In a cooking apparatus, the combination with a food-container having ingress and egress draft-passages, of a preheater adapted to act as a closure for the said in-

gress draft-passage, spacing-mechanism for holding the said container in spaced relation above the preheater, means for automatically controlling the releasing function of the said spacing-mechanism and including a setting-lever, a slotted disk, a spring for actuating the same, a tripping-lever carrying a member coacting with the edge of the said disk and entering the slot thereof, and means for actuating the said tripping-lever when so released.

24. In a cooking apparatus for conjoint fire- and fireless-cooking, the combination with a cooking compartment, of a burner arranged in heating relation thereto, a fuel-supply, means for storing energy for terminating the period of fire-cooking, cocking means for restraining the energy so stored, and automatic operating means for releasing the cocking means upon the occurrence of a predetermined condition of the cooking operation, and so permitting the stored energy to conclude the period of fire-cooking and begin the period of fireless-cooking.

25. In a cooking apparatus for conjoint fire- and fireless-cooking, the combination with a cooking compartment, of a burner arranged in heating relation thereto, a fuel-supply, means for storing energy for terminating the period of fire-cooking at a predetermined point therein, cocking means for releasing the energy so stored, automatic operating means for releasing the cocking means and upon the occurrence of a predetermined condition of the cooking operation and so permitting the stored energy to conclude the said period of fire-cooking, the said automatic means being adapted to be manually set for the variable control of the period of fire-cooking, whereby the relation of the period of fire-cooking to the period of fireless-cooking may be prearranged by the operator prior to the use of the apparatus.

26. In a cooking apparatus for conjoint fire- and fireless-cooking, the combination with a cooking compartment having an egress draft-passage and a burner-opening, of a burner arranged in heating relation to the said burner-opening, a fuel-supply, means for automatically terminating the period of fire-cooking and beginning the period of fireless-cooking upon the occurrence of a predetermined condition of the cooking operation, and means independent of the said fuel-supply for setting the apparatus preparatory to fire-cooking.

27. In a cooking apparatus for conjoint fire- and fireless-cooking, the combination with a cooking compartment having an egress draft-passage and a burner-opening, of a burner arranged in heating relation to the said burner-opening, a fuel-supply, cocking means for maintaining the apparatus in adjustment for fire-cooking, means for automatically releasing the said cocking means

- upon the occurrence of a predetermined condition of the cooking operation for terminating the period of fire-cooking and beginning the period of fireless-cooking, and 5 means independent of the said fuel-supply for manually cocking the cocking means preparatory to fire-cooking.
28. In a cooking apparatus for conjoint fire- and fireless cooking, the combination 10 with a cooking compartment having an egress draft-passage and a burner-opening, of a closure for the said passage, a burner arranged in heating relation to the said burner-opening, a fuel-supply for the said burner, cocking means for maintaining the apparatus in adjustment for fire-cooking, means for automatically releasing the said cocking means for terminating the period of fire-cooking upon the occurrence of a predetermined condition of the cooking operation 15 and beginning the period of fireless-cooking, and means independent of the said fuel-supply for manually cocking the cocking means.
29. In a cooking apparatus for conjoint fire- and fireless-cooking, the combination 20 with a cooking compartment having an egress draft-passage and a burner-opening, of a closure for the said passage, a burner arranged in heating relation to the said burner-opening, a fuel-supply, means for storing energy for terminating the period of fire-cooking, cocking means for restraining the energy so stored and maintaining the 25 said closure in its open position, and automatic operating means for releasing the cocking means upon the occurrence of a predetermined condition of the cooking operation and so permitting the stored energy 30 to conclude the period of fire-cooking and begin the period of fireless-cooking, also permitting the closing of the egress draft-passage by the said closure.
30. In a cooking apparatus for conjoint fire- and fireless cooking, the combination 35 with a cooking compartment having an egress draft-passage and a burner-opening, of a closure for the said passage, a burner arranged in heating relation to the said burner-opening, a fuel-supply, means for storing energy for terminating the period of fire-cooking, cocking means for restraining the energy so stored and maintaining the 40 said closure in its open position, and automatic operating means for releasing the cocking means upon the occurrence of a predetermined condition of the cooking operation and so permitting the stored energy 45 to conclude the period of fire-cooking and begin the period of fireless-cooking, also permitting the closing of the egress draft-passage by the said closure.
- 50 fire-cooking, cocking means for restraining the energy so stored, and automatic operating means for releasing the said cocking means upon the occurrence of a predetermined condition of the cooking operation and so permitting the stored energy to conclude the period of fire-cooking; and the closure of the said passage by the said closure. 55
31. In a cooking apparatus for conjoint fire- and fireless-cooking, the combination 60 with a cooking compartment having a controlled egress draft-passage and a controlled burner-opening, of a burner arranged in heating relation to the said burner-opening, a fuel-supply, means for storing energy for terminating the period of fire-cooking, cocking means for restraining the energy so stored, and automatic operating means for 65 releasing the said cocking means upon the occurrence of a predetermined condition of the cooking operation and so permitting the stored energy to conclude the period of fire-cooking. 70
32. In an apparatus for conjoint fire- and fireless-cooking, the combination with a cooking compartment having a burner-opening, of a burner exteriorly applied to said opening and co-acting therewith to close and 75 seal the same concurrently with the termination of the period of fire-cooking and to bear a spaced relation to it during the said period. 80
33. In an apparatus for conjoint fire- and fireless-cooking, the combination with a cooking compartment having a burner-opening and an egress draft-passage, of a closure for the said passage adapted to be opened manually prior to beginning the 85 period of fire-cooking, and to be closed automatically upon the termination of said period, a burner arranged in heating relation to the said burner-opening, and means adapted to be manually set as required by 90 the demands of ordinary cooking and to automatically control the transition of the cooking cycle from fire-cooking to fireless-cooking upon the occurrence of a predetermined condition of the cooking operation. 95
